Primary Examiner — L. A. Grabenstetter*Assistant Examiner* — Danielle Nichole Bowly(74) *Attorney, Agent, or Firm* — Alloy Patent Law; Walker Griffin Weitzel(57) **CLAIM**

The ornamental design for a curved masking tape, as shown and described.

DESCRIPTION

FIG. 1 is a front perspective view of a curved masking tape showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In FIG. 7, stiples are shown to illustrate a surface with adhesive material.

1 Claim, 5 Drawing Sheets(56)
